CATHODE RAY TUBE DEFLECTING CIRCUITS

Alda V. Bedford, Collingswood, N. J., assignor to
Radio Corporation of America, a corporation
of Delaware

Application July 25, 1935, Serial No. 33,020

5 Claims. (Cl. 250—27)

My invention relates to cathode ray tube deflecting circuits and particularly to deflecting circuits which include electrostatic deflecting plates.

It has been found, for various reasons, that the undeflected electron beam of a cathode ray tube usually does not travel down the exact center of the tube to strike the center of the fluorescent screen, light-sensitive mosaic, or other surface to be traversed by the beam. Among the reasons for this are inaccuracies in tube manufacture, the effect of the earth's magnetic field, and the presence of local magnetic fields.

An object of my invention is to provide an improved means for centering the electron beam of a cathode ray tube.

More specifically, an object of my invention is to provide improved centering means in electron beam deflecting circuits which include electrostatic deflecting plates.

20 My invention, preferably, is applied to an electrostatic deflecting circuit for a cathode-ray tube in which the deflecting plates are connected across the secondary winding of a transformer and in which the electrical midpoint of the secondary winding is maintained at approximately the same direct current potential as an electrostatic focusing electrode of the cathode ray tube. In one embodiment of my invention provision is made for impressing a direct current potential upon one deflecting plate through the transformer secondary winding and for impressing a direct current potential upon the other deflecting plate, whereby the electron beam may be properly centered.

25 In another embodiment of my invention the transformer secondary winding across which the deflecting plates are connected has a condenser inserted at its midpoint whereby a direct current potential may be applied to one deflecting plate through one half of the secondary winding and to the other deflecting plate through the other half of the said winding.

Other objects, features and advantages of my invention will appear from the following description taken in connection with the accompanying drawing, in which

Figure 1 is a circuit diagram of one embodiment of my invention, and

Figure 2 is a circuit diagram of another embodiment of my invention.

5 Referring to Fig. 1, my invention is shown ap-

plied to a television transmitter which includes a cathode ray transmitting tube 1 of a well known type. The cathode ray tube 1 comprises an evacuated envelope 2 having therein an electron gun comprising an indirectly heated cathode 3, a control electrode 4, and a first anode 6. A second anode 7 is provided which also functions as an electrostatic focusing electrode for focusing the electron beam to a small spot on a light-sensitive mosaic 8.

The mosaic 8 is so positioned that an image of the object to be transmitted may be formed thereon, and it is also so positioned that it may be scanned by the electron beam to produce picture signals in an output resistor 9 which is capacitively connected between the mosaic and the second anode 7.

10 The second anode 7 is connected to ground and the cathode 3 and first anode 6 are maintained at high negative potentials with respect to ground by means of any suitable source of potential such as batteries 11 and 12. The control electrode 4 is maintained at a negative potential with respect to the cathode 3 by means of a suitable source of potential such as a battery 13.

15 In order to deflect the electron beam in one plane, electrostatic deflecting plates 14 and 16 are provided. The deflecting means for deflecting the electron beam in a plane at right angles to the first mentioned plane has been omitted in order to simplify the drawing.

The voltage having a saw-tooth wave shape which is to be stepped up to a high voltage and applied to the deflecting plates 14 and 16 is impressed upon the input circuit of an output tube 17. The tube 17 may be a vacuum tube of the three-element type including a directly heated cathode 18, a control grid 19, and a plate 21. The input circuit of the tube 17 includes an input resistor 22 which is connected between the control grid 19 and ground, and a self-biasing resistor 23 which is connected between ground and the midpoint of a potentiometer 24 connected across the cathode filament 18. The self-biasing resistor 23 is shunted by the usual by-pass condenser 26.

20 The plate 21 is supplied with a positive potential from any suitable voltage source (not shown), the voltage being applied to the plate through the primary 27 of a step-down transformer 28.

The step-down transformer 28 is employed because the deflecting plates of the cathode-ray tube 1 are connected to the plate circuit of the output tube 17 through a rather long cable, 15

to 100 feet in length, for example. This cable includes three conductors 29, 31, and 32, as indicated by the dotted circle. By stepping down the voltage of the saw-tooth wave, more efficient transmission is obtained and the loss of high frequency components due to distributed cable capacity is reduced to a small amount.

The secondary 33 of the step-down transformer 28 is connected through the cable conductors 29 and 31 to the primary of an auto-transformer 34. The secondary of the auto-transformer is connected to the deflecting plates 14 and 16, the upper end of the secondary being connected to plate 14 through a condenser 36 and the lower end of 15 the secondary being connected to the plate 16 through a direct current connection 37.

The auto-transformer 34 is provided to step-up the voltage of the saw-tooth wave to the necessary high value for producing sufficient deflection of the electron beam.

Referring now to the electron beam centering circuit itself, a variable source of direct current potential is provided for each deflecting plate. One of these sources comprises a resistor 38 which is connected in series with another resistor 39 between ground and the positive terminal of the plate supply for the output tube 17. The other source comprises another resistor 41 also connected in series with resistor 39 between ground and the positive terminal of the plate supply.

The midpoint of the secondary 33 of the step-down transformer is connected to a variable tap or slider 42 on the resistor 38. It will be seen that there is a direct current connection from the second anode 7 through ground, through the resistor 38, the secondary 33, the cable conductors 29 and 31, and the auto-transformer 34 to the deflecting plate 16. Therefore, by moving 40 the slider 42, the direct current potential of the deflecting plate 16 with respect to the second anode or focusing electrode 7 may be adjusted.

A direct current connection is also provided between the deflecting plate 14 and the second anode 7. This connection includes a resistor 43 of comparatively high resistance value which connects the deflecting plate 14 to an adjustable tap or slider 44 on the resistor 41. It will be apparent that by adjusting the slider 44 the direct current potential of the deflecting plate 14 may be varied with respect to the focusing electrode 7. Preferably, the two resistors 38 and 41 are so connected with respect to each other that adjacent ends are of opposite polarity. The sliders 42 and 44 may be mechanically connected as indicated by the dotted block 46, whereby a movement of one slider in a direction to make one deflecting plate more positive with respect to ground simultaneously causes a movement of the other slider to make the other deflecting plate less positive with respect to ground. Thus, by adjusting the sliders 42 and 44, the electron beam may be centered on the mosaic 8.

Since the resistor 43 loads the upper half of 65 the auto-transformer secondary, it may be desirable in some cases to load the other half by means of a resistor 47 of approximately the same value. In general, however, it has been found that this additional loading of the secondary is 70 not necessary for good operation.

In the circuit shown in Fig. 2, only two cable conductors are required. In Figs. 1 and 2 like parts are indicated by the same reference numerals. In the circuit shown in Fig. 2, a condenser 75 40 is inserted at the midpoint of the secondary

of the step-down transformer 28, and another condenser 49 is inserted at the midpoint of the winding of the auto-transformer 34. Direct current potential is applied to the deflecting plate 14 by means of a connection from the variable tap 44 on the resistor 41 to one half of the secondary 33 of the step-down transformer 28. A direct potential is applied to the deflecting plate 16 by means of a connection from the variable tap 42 on the resistor 39 to the other half of the 10 secondary 33 of the transformer 28. In this way a direct current potential is applied to each deflecting plate through a cable conductor and through one section of the auto-transformer 34. The electron beam may be centered, as described 15 above, by adjusting the variable taps on the resistors 38 and 41.

In order to obtain the best electrostatic focusing of the electron beam the deflecting plates 14 and 16 should be at the same direct current potential as the focusing electrode 7. For the purpose of centering the electron beam this ideal condition is departed from to a certain extent, but the total voltage drop across each of the resistors 38 and 41 is small, about 50 volts, as compared 25 with the voltage difference between the cathode 8 and focusing electrode 7.

It has been found that when the deflecting plates are not maintained at the same direct current potential as the focusing electrode, the focusing of the electron beam is improved if one deflecting plate is maintained above the focusing electrode potential by the same amount that the other deflecting plate is maintained below the focusing electrode potential. This adjustment 35 may be made by means of a source of potential such as a battery 51 which may be adjusted to give the electrode 7 the proper potential with respect to ground.

It should be understood that my invention is 40 not limited to the particular type of cathode-ray tube illustrated. It may be applied equally well to other types of cathode-ray tubes, such as those having fluorescent screens therein for the reproduction of a picture at a television receiver.

The values of certain elements have been indicated on the drawing in ohms, megohms and microfarads. It should be understood that these values are given merely by way of example and 45 may be varied within wide limits.

From the foregoing description it will be apparent that various other modifications may be made in my invention without departing from the spirit and scope thereof, and I desire, therefore, that only such limitations shall be imposed thereon as are necessitated by the prior art and set forth in the appended claims.

I claim as my invention:

1. In combination, a cathode ray tube having 46 therein an electron gun for producing an electron beam, means including a focusing electrode for electrostatically focusing said beam, a pair of deflecting plates for deflecting said beam, said plates being on opposite sides of said cathode ray, and means for simultaneously adjusting the direct current potentials of said plates with respect to said focusing electrode.

2. In combination, a cathode ray tube having 47 therein means including a plurality of electrodes for producing an electron beam, a pair of deflecting plates for deflecting said beam, said plates being on opposite sides of said beam means for applying a periodic deflecting voltage across said plates, and means for simultaneously so adjusting the direct current potentials of said plates

with respect to one of said electrodes that said beam may be centered from a position on either side of center.

5. In combination, a cathode-ray tube having therein means including a plurality of electrodes for producing an electron beam, a pair of deflecting plates for deflecting said beam, means for applying a periodic deflecting voltage across said plates, and means for giving one of said deflecting plates a more positive direct current potential with respect to one of said electrodes and for simultaneously giving the other of said deflecting plates a more negative direct current potential with respect to said one electrode.
10. 4. In combination, a cathode-ray tube having a pair of deflecting plates and an electrostatic focusing electrode, an auto-transformer having one end of its secondary coupled to one of said plates through a direct-current connection and having the other end of its secondary connected to the other of said plates through a condenser, a pair of conductors, means for applying a periodic deflecting voltage across the primary of said transformer through said conductors, adjustable
20. 25 means for applying a direct current potential to one of said plates through said conductors whereby its direct current potential with respect to

said focusing electrode may be varied, a resistor having one end connected to the other of said plates through a direct current connection, and adjustable means for so applying a direct current potential to said other plate through said resistor that its direct current potential with respect to said focusing electrode may be varied.

5. In combination, a cathode-ray tube having a pair of deflecting plates and an electrostatic focusing electrode, an auto-transformer having a primary and a secondary, a condenser connected in series with and between two sections of said primary, one of said plates being connected to one end of said secondary through a direct current connection, the other of said plates being connected to the other end of said secondary through another direct current connection, a pair of conductors, means for applying a periodic deflecting potential across said primary through said conductors, and adjustable means for applying direct current potentials to said plates through said conductors whereby their direct current potentials with respect to said focusing electrodes may be varied for centering the cathode ray.
